C. GROOMS.

BALLOON SEARCHLIGHT.

APPLICATION FILED JULY 6, 1918.

1,390,902.

Patented Sept. 13, 1921.

C. Inventor
GROOMS.

C. Grooms, Jr.

Attorney

UNITED STATES PATENT OFFICE.

COLUMBUS GROOMS, OF EAST POINT, GEORGIA.

BALLOON-SEARCHLIGHT.

1,390,902.

Specification of Letters Patent. Patented Sept. 13, 1921.

Application filed July 6, 1918. Serial No. 243,568.

To all whom it may concern:

Be it known that I, COLUMBUS GROOMS, a citizen of the United States, residing at East Point, in the county of Fulton and State of Georgia, have invented certain new and useful Improvements in Balloon-Search-lights; and I do hereby declare the following to be a full, clear, and exact description of the invention, such as will enable others skilled in the art to which it appertains to make and use the same.

My invention relates to improvements in balloons and more particularly to search light means therefor.

An important object of this invention is to provide a search light attachment for balloons adapted to direct a ray of light in any desired direction for the purpose of detecting enemy airships.

A further object of the invention is to provide a search light attachment for balloons having means for directing a ray of light in any desired direction for the purpose of signaling distant points.

A further object of the invention is to provide a search light attachment for balloons which may be controlled from the ground in a manner similar to the control of observation balloons.

Other objects and advantages of the invention will be apparent during the course of the following description.

In the accompanying drawings forming a part of this specification and in which like numerals are employed to designate like parts throughout the same,

Figure 1 is a side elevation of a balloon having my improved search light arranged therebelow,

Fig. 2 is a central longitudinal vertical sectional view through a search light embodied in my invention, and,

Fig. 3 is a plan view of a guide for one of the light directing elements.

In the drawings wherein for the purpose of illustration is shown the preferred embodiment of my invention, the numeral 5 generically designates a balloon of the lighter than air type. Cables or cord 6 suspending from the balloon are connected

with a casing 7, as at 8.

The casing 7 carries a search light 9, having means for directing light in five directions. The casing 7 is rectangular in shape and each of its vertical sides is provided with a bull's eye 10. Its lower side is also provided with a bull's eye 10'. Arranged interiorly of the bull's eyes 10 and 10' are reflectors 11 which are conical in shape and open on their inner side. A source of light 12 may be suspended from the upper side 13 of the casing, and is disposed adjacent the inner open sides of the reflectors. Light controlling curtains 14 are mounted in bearings 16 disposed on the outside of the casing 65 and are adapted to overlie the bull's eyes. The curtains 14 are connected at their free ends with cords 16' passing through eyes 17 adjacent each bull's eye.

A frame 18 is suspended from the balloon 70 5 and below the casing 7. The frame 18 carries pulleys 19 over which the cords 16' pass. A conduit 20 is suspended below the frame 18 by brackets 21 and is adapted for the reception of the control cords 16'. With 75 reference to Fig. 1 it will be apparent that by operating any of the cords 16' from the lower end of the pipe, the light may be directed through any of the sides in the search light. The conduit 20 may be flexible 80 and extends to the ground from where the balloon is controlled.

While I have shown and described the preferred embodiment of my invention, it is understood that I may make such minor 85 changes in arrangement and construction of parts, as will remain within the spirit of the invention and scope of the appended claims.

Having thus described my invention, what I claim is:

1. In combination with an aerial body, a luminous signaling device loosely suspended therefrom having a plurality of bull's eyes for projection of light rays therethrough, shutters for the bull's eyes, pendant members to individually operate the shutters, and one of the members adapted to be held taut to steady the device as another cable is operated to move a shutter.

2. In combination with an aerial body, a 100 luminous signaling device loosely suspended therefrom having a plurality of bull's eyes

for projection of light rays therethrough, shutters for the bull's eyes, a frame suspended from the body below the signaling device and having a pendant guide tube, pendant 5 cables to individually operate the shutters passing through the tube, guide means on the frame for the cables, and one of the cables adapted to be held taut to steady the

device as another cable is operated to move a shutter.

In testimony whereof I affix my signature in presence of two witnesses.

COLUMBUS GROOMS.
